CHARLES L. ESTERLY, OF EAST CLEVELAND, OHIO, ASSIGNOR TO THE WELLMAN
BRONZE & ALUMINUM COMPANY, OF CLEVELAND, OHIO, A CORPORATION OF OHIO

FLUSH VALVE

Application filed June 12, 1929. Serial No. 370,386.

This invention particularly relates to improvements in flush valves whereby the adjusting valve utilized for controlling the length of the flushing period can be actuated without shutting off the water from the main and also without any leakage; there are also provided a new and improved assembly of adjusting valve including a screen for protecting the adjusting valve; an improved type of piston which reciprocates in the main valve body and by the movements of which the flow of water from the main directly through the flush valve to the outlet is permitted or shut off, such new type of piston being formed so as to effect the automatic washing out of accumulated sediment by the flow of water from the main through the flush valve; and an improved relief valve guide or pilot by means of which the relief valve head is centered when it is forced down upon its seat by a spring after being released from the pressure of the push bar which is actuated by the flush valve handle. Other detail improvements will appear hereinafter and be fully explained by the specification and upon reference to the accompanying drawings.

The annexed drawings and the following description set forth in detail certain means embodying my invention, such means constituting, however, but one of the forms in which the principle of the invention may be illustrated.

In said annexed drawings:

Figure 1 is a central vertical section of the improved valve connected to inlet and outlet conduits of which fragmentary portions are shown, the several parts of the valve being in the respective positions occupied when in closed or non-flushing position;

Figure 2 is a plan view of the elements shown in Figure 1;

Figure 3 is a fragmentary horizontal section; taken in the plane indicated by the line 3-3, Figure 1;

Figure 4 is a fragmentary vertical section, taken in the plane indicated by the line 4-4, Figure 3;

Figure 5 is a perspective view of a relief valve guide or pilot;

Figure 6 is a view similar to Figure 1 showing, however, the respective positions of the several valve parts shortly after the actuation of the operating handle of the valve;

Figure 7 is a central vertical section of a screened adjusting-valve assembly unit removed from the valve body;

Figure 8 is a side elevation of the parts shown in Figure 7;

Figures 9 and 10 are horizontal sections, taken, respectively, in the planes indicated by the lines 9-9 and 10-10, Figure 6;

Figure 11 is a horizontal section, taken in the plane indicated by the line 11-11, Figure 8;

Figures 12 to 17, inclusive, are detached axial sectional views of the several parts of the screened adjusting valve assembly, prior to their assembling, the same being shown aligned in the order of their assembling, Figure 12, showing the adjusting screw packing nut, Figure 13, the adjusting screw proper, Figure 14, the packing gland of the adjusting valve body, Figure 15, the adjusting valve body, Figure 16, the adjusting valve protective screen, and Figure 17, a portion of the screen housing, the adjusting valve body shown in Figure 15 being provided with means forming the remainder of the screen housing, as hereinafter fully described; and

Figures 18 to 23 are elevations respectively of the several parts shown in Figures 12 to 17.

Referring to the annexed drawings in which the same parts are indicated by the same respective numbers in the several views, the chambered flush valve body 1 is formed with a guideway 2 to accommodate the vertical reciprocations of a piston comprised of the top member 13 and the bottom member 16 which are threaded together, as plainly shown in Figures 1 and 6, the top member 13 alone sliding upon the surface of the guideway 2, as also plainly shown in said figures. The chambered valve body 1 is formed with an internally-threaded boss 3 adapted for connection to a nipple 4 which leads to the water main. The valve body 1 is also formed with an externally-threaded boss 5 adapted for connection, through the medium of a nut 100

28 and a nut gasket 29, to a conduit 6 leading to the waste water outlet. Another externally-threaded boss 7 provides means for the securing of the operating handle and 5 push rod parts to the valve body, as herein-after fully explained, and an upstanding boss 8 secured outside the valve body 1 proper provides means for securing the adjusting valve parts, which also will be herein- 10 after described in detail. An annular rim 9 which surrounds the chamber 21 connecting the inlet chamber 10 and an outlet chamber 10' forms a seat for the main valve element which permits the flow of the water directly through the valve body for flushing 15 purposes. An internally-threaded cap 11 covers the top of the valve chamber, an annular sealing gasket 12 being utilized, as plainly shown in Figures 1 and 6. The 20 joint adjacent the connected screw-threaded portions of the piston top 13 and the piston bottom 16 is sealed by means of a cup washer 18 which is formed with an annular inwardly-extended horizontal portion 18' confined 25 between the bottom face of an enlarged bottom portion 14 of the piston top 13 and the top face of an annular enlarged portion 15 formed upon the piston bottom member 16, this cup washer 18 being also formed with 30 a downwardly-extended annular skirt 18' closely registering with the surface of the guideway 2 beneath the peripheral sliding piston top 13. Contained within the piston 35 top of a refill plug 23 through the medium of a relief valve washer 22 which forms the sealing and seating means for the relief valve upon the plug 23, this relief valve 19 being normally held in seated position by a 40 relief valve coil spring 26 mounted at one end around the centralizing cap portion 31 of the relief valve 19 and abutting at the other end the spaced head ribs 27 and the central hub or head 27' forming parts of the piston top 45 member 13. Piston member 14 is formed with an upwardly-extended stop member 27' to limit the opening movement of the piston.

The valve member proper which seats upon the annular rim 9 is completed by the piston seat washer 24 contained within a countersunk chamber 16' formed in the bottom of the piston member 16, said washer 24 resting upon a peripheral annular shoulder 30 formed on the refill plug 23, the latter being 50 screw-threaded above said shoulder 30 into the lower piston member 16, as plainly shown in Figures 1 and 6. The relief valve is completed by a valve stem 20 secured at its top end in the spring-centralizing head member 31 and extended downwardly through the refill plug 23 and the passage 21 and into the discharge conduit 10'. In order that the relief valve head member may be centered when the valve is permitted to be seated under the 55 action of the spring 26, I provide the valve

stem 20 with, or form thereon, a pilot or guide member 25 whose upper face 46 is disposed adjacent the lower face of the washer member 22, this pilot or guide 25 being plainly shown in Figure 5, and having the central hole 45 for the passage therethrough of the stem 20. The pilot 25 consists of an upper portion 47 rectangular in cross section and a conical lower portion 48, the downwardly tapered surface of this lower conical portion 48 forming means for centering the relief valve, inasmuch as the top portion 47 thereof is rectangular and the longer dimension of the top face 46 is substantially equal to the diameter of the chamber in the refill plug 23, as plainly shown in Figure 4. The side surfaces of the top portion 47 of the guide 25 are trimmed off plane to form the vertical face portions 47' which merge at their lower ends into the top of the peripheral surface portion of the conical lower guide member 48, as plainly shown in Figure 5.

It will be noted in Figure 1 that the annular bottom portion of the piston member 16 is flared outwardly and downwardly and is disposed below the center of the inlet passageway 10 and also in the line of water travel through the passageway 10 to the passageway 21. This particular construction is for the purpose of enabling the flushing water to wash off any sediment which may have deposited upon the surface of the piston part 16, and thus prevent the accumulation of sediment upon the piston surface.

The valve actuating means are controlled through the handle 32 which is formed at its inner end with an enlarged flange member 33 whose outer face abuts a correspondingly shaped flange member 43 formed upon a hub member 42 secured to one end of a push bar 41. The inner end of this push bar 41 abuts the relief valve stem 20, when the valve is in idle non-flushing position, as shown in Figure 1. The flange members 33 and 43 and the outer end of the push bar 41 are contained within the chamber of a sleeve 37 closely fitted within the main body boss 7 and having an external enlarged flange portion 35 abutting an inner gasket member 36 disposed adjacent the outer face 7' of the boss 7, the whole assembly being securely locked together through the medium of the handle retaining member 49 which engages an externally-threaded end portion of the boss 7. The housing for the actuating flange members 33 and 43 is completed by the bottom wall 37' of the sleeve 37 which forms an abutment for one end of a push bar spring 44, the other end of said spring 44 encircling the hub member 42 and abutting the push bar flange 43. A guide for the push bar 41 is formed by a hub member 38 extended inwardly from the bottom wall 37' of the sleeve 37, a water tight joint for the outer open end of the hub 38 being formed through the medium of a push 100

bar packing nut 39 and a push bar packing member 40, as plainly shown in Figures 1 and 6.

The wall of the body member 1 is formed adjacent the boss 8 with a by-pass hole 50 which leads at one end into the chamber of the main body 1 above the guideway 2 and at the other end into the chamber of the boss 8. This boss 8 contains the adjusting screw 62 which is threaded at its lower end and adapted for engagement with and vertical adjustment in an adjusting valve body member 52. The lower valve portion proper of the adjusting screw 62 cooperates with seat portion 54' formed in the body member 52 adjacent the top of a hole 54 which connects a lower open-end screen portion 70 of the valve body 52 and side openings 53 opening into an annular chamber 51 contained within the boss 8 and into which the one end of the by-pass valve hole 50 leads. The screen housing portion 70 of the valve body 52 is internally-threaded and adapted to cooperate with the externally-threaded upper portion of a lower screen housing member 55 which is formed at its lower end with a plurality of side wall openings 56 leading into the inlet chamber 10. It is evident therefore that, when the adjusting screw 62 is raised from its seated position upon the member 54', there is an open passage for water from the inlet chamber 10 to the top of the chamber within the main body 1, the amount of communication depending upon the adjustment of the lower valve portion of the adjusting screw 62 relative to the seat member 54'. A screen member 71 is positioned between the holes 56 leading from the inlet chamber 10, and the passage 54 leading from the housing member 70, the latter and the complementary housing member 55 being provided with annular groove portions in their body members respectively for receiving and seating the upper and lower edges of the screen 71, these groove portions being indicated by the number 68 in the housing member 70 of the valve body 52 and the number 69 in the housing member 55.

An adjusting packing gland 57 is sleeved around the valve body member 52 of the adjusting screw 62 and, through the medium of a follower 59 and a packing rubber 60 seated upon an annular flange 61 formed upon the valve body 52, serves to hold the valve body 52 tightly within the chamber of the boss 8 and provides a leak-proof joint above the annular chamber 51. The lower face of the valve body 52 engages an adjusting valve fiber gasket 66 which is seated upon an inner annular shoulder 67 formed in the body of the boss 8. The upper end of the valve body 52 is externally-threaded and engages with an adjusting screw packing nut 63 which covers and surrounds an adjusting screw packing 64 to prevent leakage along the ad-

justing screw 62. An outside cover member 65 is provided for the packing gland 57 and the packing nut 63 and the top of the adjusting screw 62, this cover 65 being externally-threaded at its lower end and engaging with an internally-threaded flange 8' formed upon the top of the boss body 8.

The screen 71 serves effectively to filter the fluid which afterwards passes through the by-pass 50 and thus removes the probability of this by-pass and the adjusting valve parts and the guideway 2 being damaged or clogged by sediment. This construction particularly prevents the possibility of the clogging of the space between the adjusting screw 62 and the seat 54' and thus eliminates any disturbance of the adjustment setting. Furthermore, the particular screen assembly shown is easily applied and removed, economically produced and installed, and very satisfactory in operation.

I also direct attention to the fact that the adjusting screw assembly obviates any leakage from the chamber of the boss 8 when the adjusting screw proper 62 is actuated for changing the length of the flushing period without shutting off the water from the main. This adjustment is effected by removing the cover 65 and turning the screw 62 by a suitable tool through the medium of the groove 62' in the head of the screw 62, the adjusting screw packing 64 preventing any leakage along the periphery of the screw 62, and the packing rubber 60 preventing any leakage along the inter-engaging screw threads formed upon the packing gland 57 and the inner wall of the boss 8.

It is well understood by those skilled in the art that the period of flushing is regulated by the time necessary to fill the chamber above the piston part 14 with water which is by-passed through the conduit 50, and this period is regulated by the setting of the adjustment screw 62. If this screw 62 is adjusted to increase the size of the space between the seat 54' and the lower valve portion of the screw 62, water is by-passed through the conduit 50 in greater quantities and the time necessary for filling the chamber above the piston part 14 and seating the washer 24 upon the annular rim 9 is shortened and thus the flushing period during which the water passes directly from the fitting 4 to the fitting 5 is also shortened. Conversely, the adjustment of the screw 62 so as to make the space above the seat 54' smaller results in a longer flushing period.

What I claim is:

1. A flush valve including a casing formed with an inlet and an outlet and a guideway; a main valve member formed with a guide portion operable in said guideway; a relief valve including an upper seat portion and a downwardly extended stem; means for actuating said stem to open said relief valve; 125

means tending to hold the relief valve to its seat; and a guide member secured to the upper part of said stem for centralizing the relief valve upon its seat, said guide member having an upper rectangular portion with a dimension substantially equal to the diameter of the chamber in which the stem is actuated, said guide member having also a lower conical portion.

10 2. A flush valve including a casing formed with an inlet and an outlet and a guideway; a valve member formed with a guide portion operable in said guideway; a manually actuated relief valve whose opening relieves the 15 pressure above the aforesaid valve member and permits the latter to move upwardly in said guide portion to open; means forming a by-pass from the inlet to the casing chamber above the valve member; an adjusting valve 20 for regulating the fluid passage through the by-pass; an adjusting valve body member formed with a seat portion for the adjusting valve, said valve body member being also formed with a bottom open end chambered 25 portion having an upper annular groove section; a screen housing threaded at its upper end into said chambered portion, said housing being formed with a lower annular groove section; and a cylindrical screen seated at 30 its ends within said grooves, said housing being formed with a plurality of holes communicating with said inlet and forming a part of said by-pass.

3. A flush valve including a casing formed 35 with an inlet and an outlet and a guideway; a valve member formed with a guide portion operable in said guideway; a manually actuated relief valve whose opening relieves the pressure above the aforesaid valve member 40 and permits the latter to move upwardly in said guide portion to open; an open-top lateral boss formed integrally with the casing and having a chamber portion; a by-pass conduit formed in the wall of the boss and communicating with the casing chamber above the valve member and also with the chamber in the boss; an adjusting valve body contained within said boss chamber and having a passage therethrough communicating with said 45 inlet and also with the chamber in the boss; a packing gland sleeved around said valve body and having external screw-threaded engagement with the top portion of said boss; a follower and packing rubber below said 50 gland and in contact with the inner boss wall, said valve body being formed with an annular flange upon which said packing rubber rests; a screw valve member adjustably secured within said valve body, the latter 55 being formed with a valve seat portion for said screw, the latter extending outwardly beyond said valve body; leak-proof packing surrounding the end of said valve body and the adjacent portion of said screw; and a 60 removable cover secured to the open top portion 55

tion of said boss and enclosing the top of said screw, said gland and said leak-proof packing.

Signed by me this 13th day of May, 1929.

CHARLES L. ESTERLY.
